UNITED STATES PATENT OFFICE.

WILLIAM D. FERRIS, OF SHARON, PENNSYLVANIA, ASSIGNOR TO SHARON HARDWARE MANUFACTURING COMPANY, OF SHARON, PENNSYLVANIA, A CORPORATION.

DOOR-HANGER.

1,243,499.

Specification of Letters Patent. Patented Oct. 16, 1917.

Application filed February 19, 1917. Serial No. 149,495.

To all whom it may concern:

Be it known that I, WILLIAM D. FERRIS, a citizen of the United States, and a resident of the borough of Sharon, county of Mercer, and State of Pennsylvania, have invented certain new and useful Improvements in Door-Hangers, of which the following is a specification.

This invention relates to door hangers, and has for its object to provide a hanger particularly adapted for double doors, the sections of which are hingedly connected.

A further object of this invention is to provide a door hanger which may be used on a track lying parallel throughout its entire length to the supporting frame or door jamb.

A still further object of the invention is to provide a hanger having a pivotal connection with the door supported thereby, and having a stop limiting the travel of the carrying sheaves on the track when the door is moved to closed position.

Still another object of the present invention is to provide a door hanger which may be interchangeably used on either right or left opening doors.

These objects, together with attendant advantages will be apparent as the invention becomes better understood by reference to the specification, and drawings forming a part thereof, throughout the several views of which like characters of reference have been used to indicate like parts.

Referring to the drawings Figure 1 is a front view of right and left double doors equipped with my improved hanger, one of the doors being shown in open position.

Fig. 2 is a perspective view of a double door in open position with the hanger secured thereto.

Fig. 3 is a plan view of the door shown in Fig. 2 in partly closed position.

It has heretofore been proposed to provide double doors with hangers by means of which it was possible to move the doors to open position, in which position they nested parallel to the building to which they were applied. In such constructions it has been necessary to provide a specially designed bracket and tracks either curving away from the door jamb, or lying at an inclination thereto. One of the disadvantages of such a construction is that it is necessary for a dealer to carry separate brackets and tracks

for both left and right opening doors. One of the purposes of this invention is the adaptation of a hanger for use on a straight track lying parallel throughout its entire length to the door frame. Such a track may 60 be carried in stock in various lengths which may be cut as found necessary, and secured in position by the use of standardized brackets.

Referring more particularly to the drawings, I have shown a garage or other building 1 provided with a straight track 2 adjacent the door frame and secured in position by means of suitable brackets or angle irons 3. In order to show the possibility of 65 using the hanger with doors opening in opposite directions I have shown the same in Fig. 1 as applied to right and left opening double doors 4 and 4' respectively. For the sake of clearness a set of doors is shown in 70 each extreme position.

The hanger in its preferred form may comprise a carrier 5 preferably channel shaped and secured at its upper end to a yoke 6, the opposite ends of which are bifurcated or spaced to provide journals for the grooved carrying sheaves 7. The carrier may have a stud 8, or the like, projecting from its lower side to form a pivotal mounting for the door connecting link 9. The 80 outer end of the link is formed with an opening for the reception of the pin 10 rigidly secured to the plate 11 carried by the inner section of each of the double doors.

From the foregoing it will be apparent 90 that doors equipped with my improved hanger may be opened and closed in a minimum amount of space. Referring more particularly to Fig. 3, the different positions assumed by the door sections in their travel 95 from closed to open position, or vice versa, may be readily understood. During such movement the link 9, pivotally connected at each end, swings freely with each change in the angular relationship between the door sections and the door frame. In fully 100 opened position, as shown more clearly in Fig. 2, the link extends over a portion of each of the door sections so that the same may lie flat against the building. In prior 105 door structures in which a plurality of hinged doors are used, the hanger mechanism is such that when the doors are open they extend at right angles to the hanger track and in such position obstruct more or 110

less of the door opening; but with my invention, the door sections, when opened, turn away from the door opening so as to leave the same unobstructed. Obviously, it is not necessary that the door sections, when opened, should be exactly parallel with the track, but this purpose of the invention will be accomplished if the sections are turned sufficiently beyond a right angle to leave the door opening unobstructed; and it is such meaning that I wish attached to the expression "substantially parallel to each other and to the track", as used in the claims.

Unless a stop or the like is provided with the construction already described, the carrying sheaves instead of occupying the full line position A shown in Fig. 1, may readily travel to what may be termed the interfering position B indicated in dotted lines. In such event closing of the other set of doors would be rendered comparatively difficult. For this reason I have shown the carrier as provided with a downwardly projecting stop 12 adapted to intercept the link 9 during its swinging motion, and limit the movement of the same. This insures a travel of the carrying sheaves in the direction of the arrow C during the final closing movement of the door, whereby they are prevented from extending beyond the center of the track into interfering position. If a single set of doors is used, the stop makes it possible to utilize a comparatively short section of track without fear of derailment.

While I have described the preferred embodiment of my invention it will be obvious that changes may be made therein within the scope of the appended claims.

Having thus described my invention, what I claim as new, and desire to secure by Letters Patent, is:—

1. In a door structure, the combination of a straight track rigidly mounted parallel to the door opening, a plurality of hingedly connected doors the outer one of which is hinged at one side of said door opening, a hanger mounted to travel on said track, and means connecting said hanger with the inner door allowing it to move laterally of the track in a manner permitting said doors to fold back substantially parallel to each other and to said track.

2. In a door structure, the combination of a straight track rigidly mounted parallel to the door opening, a plurality of hingedly connected doors the outer one of which is hinged at one side of said door opening, a hanger mounted to travel on said track, and a horizontally swinging member extending between said door hanger and the inner door and pivotally connected to both in manner

permitting said doors to fold back substantially parallel to each other and to said track.

3. In a door structure, the combination of a straight track rigidly mounted parallel to the door opening, a plurality of hingedly connected doors, the outer door having a fixed hinge, a hanger mounted to travel on said track, a horizontally swinging member extending between said door hanger and the inner door and pivotally connected to both in manner permitting said doors to fold back substantially parallel to each other and away from the door opening, and means for preventing the movement of said hanger into interfering position.

4. In a door structure, the combination of a straight rail rigidly mounted parallel to the door frame, a plurality of hingedly connected doors, the outer door having a fixed hinge, a door hanger movable on said rail, and means connecting said hanger and the inner door comprising a stud extending downwardly from the hanger, a plate secured to the door and having a pin extending upwardly therefrom, and a link connecting said stud and pin below the hanger and above the door, whereby the latter may be folded back parallel to the other door and the track.

5. In a door structure, the combination of a suitable support; a plurality of hingedly connected doors, the outer one of which is hinged to said support; a track fixed with relation to said support and parallel therewith throughout its entire length; a hanger movable upon said track, and a link connecting said hanger and one of the inner doors, said link having a limited rotative movement above the door and below the hanger.

6. In a door structure, the combination of a suitable support, a plurality of hingedly connected doors, the outer one of which is hinged to said support, a track fixed with relation to said support and parallel therewith throughout its entire length, a hanger movable upon said track, said hanger comprising a carrier having a stud projecting downward therefrom, a pin projecting above the inner door, a stop projecting downward from said carrier, and a link pivotally connected with said stud and pin and adapted, as the doors are opened, to abut against said stop.

In testimony whereof I have affixed my signature in the presence of two witnesses.

WILLIAM D. FERRIS.
